UNITED STATES PATENT OFFICE.

CHARLES ROBERT MAYHALL, OF ARROYO GRANDE, CALIFORNIA.

APPARATUS FOR THE PROPULSION OF SHIPS.

961,306.

Specification of Letters Patent. Patented June 14, 1910.

Application filed June 11, 1909. Serial No. 501,635.

To all whom it may concern:

Be it known that I, CHARLES R. MAYHALL, a citizen of the United States, residing at Arroyo Grande, in the county of San Luis Obispo and State of California, have invented certain new and useful Improvements in Apparatus for the Propulsion of Ships; and I do declare the following to be a full, clear, and exact description of the invention, such as will enable others skilled in the art to which it appertains to make and use the same.

This invention relates to an improved apparatus for the propulsion of ships by means of compressed air.

With the arrangements now in use, it is often exceedingly difficult to handle and shift vessels in confined quarters, and auxiliary appliances, such as tugs, are often required to accomplish the purpose desired and which in addition to consuming considerable time in performing the operations are also expensive.

The object of this invention, therefore, is to provide simple means carried by the vessel whereby it may be turned on its own axis, moved bodily sidewise, driven backward or forward, or shifted in any other way required without the necessity or expense of employing outside assistance.

With the foregoing and other objects in view, the invention consists of certain novel features of construction, combination and arrangement of parts, as will be more fully described and particularly pointed out in the appended claim.

In the accompanying drawings, Figure 1 represents a horizontal section through the hull of a vessel equipped with this improvement; Fig. 2 is a longitudinal vertical section thereof.

In the apparatus shown for carrying out this method, a compressed air tank 1 is arranged in any part of the boat where it will occupy the least space and it may be supplied with air from any suitable source, a pump 2 operated in any suitable manner being preferably arranged for this purpose. Connected with this air tank are pipes 3 and 4 which open through the front and rear of the boat, respectively, and are provided with outwardly opening discharge valves for ejecting a stream of compressed air therethrough to propel the vessel in the di-

rection in which it is desired to go and which may be used either in connection with the ordinary propellers or without them. Branch pipes 5 and 6 are preferably arranged near the front end of the boat and extend laterally through opposite sides thereof below the water line for a purpose to be described. Similar pipes 7 and 8 are arranged near the rear of the boat and extend laterally through opposite sides thereof below the water line to discharge jets of air for turning the boat in the desired direction. It will be understood that these pipes are provided with suitable valves to permit the discharge of the compressed air and to prevent the admission of water into the pipes. The air tank or tanks, as 1, are preferably provided with steam pipes 9 extending therethrough for the purpose of heating and expanding the air contained therein to increase the pressure thereof.

In the operation of a boat equipped with this apparatus, when it is desired to propel the boat forward, the valve at the outer end of the pipe 4 at the rear of the boat is opened thereby causing the jet of compressed air to be forced into the water which causes the boat to be propelled rapidly forward. To drive the boat in the opposite direction, the valve in the pipe 3 at the front of the boat is opened which instantly reverses the direction and moves the boat rearwardly, an ordinary rudder 10 being preferably used for steering when the boat is being moved longitudinally. To prevent a head-on collision, the pipe 6 at the side of the boat is opened to turn the boat to the right and to turn it to the left, the pipe 5 is opened. The captain's bridge is preferably provided with emergency levers (not shown) connected with the valves in the respective pipes to provide for the quick action of the boat, thus making a collision practically impossible.

To turn the boat entirely around on its own axis, as on a pivot, the valves in pipes 6 and 7 are opened thereby forcing a jet of air to the left at the front end of the boat and a jet of air to the right at the rear end thereof, which turns the boat in a very small space and in case of a battleship or fleet of ships adapts them to take position in front of an enemy broad side for the operation of the star-board guns, and then turning on a

5 pivot by opening the proper valves in the laterally extending pipes at the front and rear of the boat and presenting the port guns for operation thereby avoiding running in a circle and avoiding injury to their own boats. To move the boat to one side, for instance to the right, the valves in the pipes 10 and 8 are opened forcing jets of air into the water and thus moving the boat in the opposite direction, to cause it to take any 15 position desired.

By the use of this improved means, it has been found that a boat may be handled with perfect ease in any direction and that when 15 used for propelling, the speed is increased one-third.

20 From the foregoing description, taken in connection with the accompanying drawings, the construction and operation of the invention will be readily understood without requiring a more extended explanation.

25 Various changes in the form, proportion and the minor details of construction may be resorted to without departing from the principle or sacrificing any of the advantages of the invention, as defined in the appended claim.

Having thus described my invention, what I claim is:

A vessel provided with compressed air 30 tank, a pipe extending longitudinally from end to end of the vessel and discharging through the center of opposite ends thereof below the water line, valves arranged near the ends of said pipe, laterally extending 35 pipes arranged near the front end of the vessel and opening through the opposite side walls thereof at points diametrically opposite, and similar pipes arranged at the rear end of the vessel, said lateral pipes having 40 valves arranged therein, means for communication between the first-mentioned pipe and compressed air tank and steam pipes extending longitudinally through the tank to heat and expand the compressed air therein in 45 order to increase the pressure thereof.

In testimony whereof I have hereunto set my hand in presence of two subscribing witnesses.

CHARLES ROBERT MAYHALL.
